SLIDER FOR SLIDE FASTENERS

Noel J. Poux, Meadville, Pa., assignor to Lion Fastener, Inc., Meadville, Pa., a corporation of Delaware

Application January 28, 1931, Serial No. 511,753

8 Claims. (Cl. 24—205)

It is desirable to provide locks for sliders of slide fasteners so that the slide may be moved along to any position on the fastener and locked in the adjusted position. The present invention is designed to provide such a lock securing the slider firmly in any adjusted position, yet one that will be readily released through the mere operation of the tab. The invention contemplates the normal engagement of the slider through the locking means, said means being unlocked through the action of the tab when adjusting the slider. The invention also contemplates the housing of the locking means by the tab lug so that while it is of ample size and strength it is practically concealed. Features and details of the invention will appear from the specification and claims.

A preferred embodiment of the invention is illustrated in the accompanying drawing as follows:

Fig. 1 shows a side elevation, partly in section, of the slider in place on a fastener, the locking means being retracted, or out of locking position.

Fig. 2 a plan view of the slider in place on a fastener.

Fig. 3 a view similar to Fig. 1, but with the locking means in locked position.

Fig. 4 a section on the line 4—4 in Fig. 3.

Fig. 5 a perspective view of the locking pawl.

Fig. 6 a sectional view of the tab lug on the line 6—6 in Fig. 7.

Fig. 7 a side elevation of the tab lug removed.

Fig. 8 a side elevation of a modified form of slider with the parts in locking position.

Fig. 9 a similar view with the parts in retracted, or unlocked position.

Fig. 10 a perspective view of the pawl in the modification of Figs. 8 and 9.

Fig. 11 a plan view of one of the guide plates detached.

1 marks a stringer, 2 the usual rib along the fastening edge of the stringer, 3 the fastener members provided with the usual projections 4 and recesses 5, 6 guide plates of the slider, and 7 the wedge, or spreading guide of the slider. The slider is provided with the usual guide flanges 8.

The tab lug 9 is preferably T-shaped in cross section having a longitudinal covering plate 9a with an inwardly extending web 9b. One end of the plate 9a is turned in at 10 against the end of the web 9b with an extension 10a which is adapted to extend through registering perforations 11 in the plates 6 and spreader 7. The extension 10a, therefore, forms a means for locking the two guide plates together. The opposite end of

the plate 9a is bent inwardly at 12 around the end of the web 9b and has an extension projecting into a perforation 13 in the guide plate and is riveted over on the under-side of the plate, thus securing the guide lug on the plate.

The guide plate has a pawl opening 14 through which a pawl finger 15 extends. The pawl finger is carried by a pawl 16 which is arranged under the plate 9a and extends the full length of the plate. This pawl is U-shaped, as clearly shown in Fig. 5 and the bend of the U extends through a notch 17 in the web 9b adjacent to the end 10. In the structure shown in Fig. 1, this notch is of sufficient size to form a loose connection and thus permit the pawl to swing freely.

A tab 18 has a bifurcated end 19 which straddles the plate 9a and the bifurcated ends have in-turned fingers 20 which extend under the pawl 16. The fingers are of such size, or width that when the tab 18 is turned to a position at right angles to the slider plates they retract the pawl 16 and thus unlock the slider, as clearly shown in Fig. 1. When, however, the tab is swung into alignment with the plates, as shown for instance in Fig. 3, the pawl can swing carrying the locking finger through the perforation 14 into engagement with the fasteners 3, thus locking the slider. The tab operating on a projection 21 tends to swing the pawl into locking position. It will be noted that the outward movement of the pawl is limited so as to maintain the engaging end of the locking finger in close proximity to the members 3 as the slider is moved along over the members so that the pawl is maintained in position to readily respond to the slight vibration, or movement of the slider on the members to swing into locking engagement and that the locking finger of the pawl is diagonally across the lug from the swinging support at the notch 17 so that when the pawl is in locking position and is initially engaged any attempt to move the slider merely forces the pawl more firmly into locking engagement.

In the modification shown in Figs. 8, 9 and 10, the guide plate, tab lug and tab are of exactly the shape as shown in Figs. 1 to 5. The pawl 22, however, is formed of resilient metal and the U-bend forms a close fit in the opening formed by the notch 17. The spring of the pawl is such as to yieldingly force the finger 23 into locking engagement, but when the tab is turned out to right angles to the plates, as shown in Fig. 9, the pawl is unlocked. Thus the pawl is in locked position, but may be unlocked by swinging the tab.

In both structures the pawl is entirely concealed by the lug. The U structure affords an easy and convenient means for securing it under the lug and the notch can be readily formed in the web, 5 the pawl put in position before the end 10 is bent into closed position.

What I claim as new is:—

1. In a slider for slide fasteners, the combination of guide plates; a tab lug on one of the plates, 10 the lug having a longitudinal web; a pawl of U form straddling the web and having a pawl finger adapted to lock the slider; and means on the tab lug actuating the pawl.
2. In a slider for slide fasteners, the combination of guide plates; a tab lug on one of the plates, 15 said tab lug having a longitudinal web and a cover plate; a pawl of U form straddling the web and having a pawl finger adapted to lock the slider; and a tab having a bifurcated end with 20 inturned projections extending under the pawl and adapted to actuate the pawl.
3. In a slider for slide fasteners, the combination of guide plates; a tab lug on one of the plates, 25 said tab lug having a cover plate and a longitudinal web; a pawl of U-shape swingingly mounted on the web by a loose connection at its bend and having a pawl finger adapted to lock the slider; and means on the lug retracting the pawl.
4. In a slider for slide fasteners, the combination of guide plates; a tab lug on one of the plates, 30 said tab lug having a cover plate and a longitudinal web; a pawl of U-shape swingingly mounted on the web by a loose connection at its bend and having a pawl finger adapted to lock the slider; a tab on the lug; and means on the tab actuating the pawl.
5. In a slider for slide fasteners, the combina-

tion of guide plates; a tab lug on one of the plates having a cover plate and an inwardly extending longitudinal web; a U-shaped pawl straddling the web and secured thereto, the pawl being resilient and having a pawl finger extending into locking position; and a tab on the lug adapted to retract the pawl.

6. In a slider for slide fasteners, the combination of guide plates; a tab lug on one of the plates having a cover plate and an inwardly extending 10 longitudinal web; a U-shaped pawl straddling the web and secured thereto, the pawl being resilient and having a pawl finger extending into locking position; and a tab on the lug having bifurcated ends with inwardly extending projections under 15 the pawl adapted to actuate the pawl.

7. In a slider for slide fasteners, the combination of guide plates having registering perforations; a tab lug of T-shape cross-section forming a cover plate with an inwardly extending web 20 and having an end extending through the perforations and securing the guide plates together; means securing the opposite end of the tab lug to one of the plates, a pawl on the lug secured to the web of the lug; and a tab on the lug actuating 25 the pawl.

8. In a slider for slide fasteners, the combination of guide plates having guide surfaces thereon adapted to operate fastener members; a tab lug on one of the plates; a pawl housed by the lug 30 pivotally mounted at one end thereof to one end of the lug and having its locking end at the opposite end of the lug, said locking end of the pawl being maintained closely to slider locking position; and a tab on the lug engageable with 35 the pawl at its locking end for releasing the pawl.
